CONTAINER FLATTENING APPARATUS
Victor H. Hasselquist, 1655 Preston Ave., Akron 5, Ohio
Filed June 22, 1959, Ser. No. 822,018
4 Claims. (Cl. 100—233)

This invention relates to apparatus for crushing or flattening containers such as tin cans for compact disposal or the like.

The apparatus of this invention is well adapted for hand operation and an important feature of all embodiments of my invention is that the container is progressively or partially flattened, step by step upon successive operations of an operating handle or lever which, in the hand operated form are operations that are readily performed. The can is self feeding by gravity and the flattened or crushed portion falls down clear of the jaws as the crushing cycles are repeated.

The jaws are relatively inclined to form a gravity hopper, and remain so inclined even when the jaws are closest together, that is, at their minimum spacing. The apparatus includes a frame and fixed jaw, a movable jaw pivoted to the frame below the lower end of the can crushing portion, the handle or lever referred to, machine element means connected between the frame, the handle and the movable jaw for causing the movable jaw to move toward and away from the fixed jaw upon oscillation or "pumping" of the handle.

It is an important feature of this invention that the maximum force that must be applied to the handle to crush the container is relatively small because the container is only partially crushed along its length with each stroke, and the flattened or crushed lower portion of the container progressively drops out from between the ever relatively inclined jaws on each retract stroke of the handle.

When engaging a container, the minimum spacing of the lower, or work portions of the inclined jaws is equal to the final thickness of the flattened container, and since the jaws are always relatively inclined, the container is flattened at the lower zones of the inclined jaws and hence is given a series of relatively easily imparted "nips," each nip requiring but little force, and since every nip is applied between the lower ends of the diverging jaws, the crushing force is always relatively highly localized and thus can be readily applied. The container is not and cannot be fully crushed or flattened on one, or usually, even on two strokes of the handle, but each stroke quickly and easily does its share and the entire operation is completed with ease. Nothing need be done to either feed the container through the jaws during the flattening operation nor to remove the flattened container, except to effect a series of readily performed oscillations of the handle.

It is an important feature of the invention that the angle between the jaws is such that the friction between the can and the jaws during the crushing stroke is sufficient to keep the can from sliding upwardly, and no teeth that puncture the can or otherwise restrain it from falling due to the force of gravity on the retract stroke are provided on either jaw, which teeth might pierce the can and keep it from feeding itself through the jaws under gravity.

Also, in the preferred embodiment of my invention the frame and movable jaw member become progressively wider from top to bottom in order to accommodate the increased width of the can as it is flattened and yet serve to keep the uncrushed can in good vertical alignment at the beginning of the flattening operation.

In a preferred form of the invention, there is a toggle type link mechanism connected between the operating

2

lever and the frame which serves to provide maximum leverage to the beginning of the crushing stroke, at which time resistance to crushing is the greatest, particularly when a fresh can is introduced into the apparatus.

Having described briefly the general nature of the apparatus embodying my invention, a more detailed description of two embodiments thereof follows.

In the drawings:

FIGS. 1-9 illustrate one embodiment of my invention wherein the machine element means for operating the crusher jaw includes a gear and sector arrangement, FIG. 1 being a perspective view thereof;

FIGS. 2-9 are vertical sections showing a cycle of operation and FIG. 2 shows an uncrushed container between the jaws;

FIG. 3 shows the movable jaw advanced after the first stroke of the handle, the container having received its first "nip";

FIG. 4 shows the apparatus after the following retract stroke, the container having slipped down from the positions of FIGS. 2 and 3 to present an uncrushed portion to the lower end portions of the jaws ready for the next "nip";

FIGS. 6-9 show successive cycles, a fully flattened container being shown in FIG. 9, ready for gravity release upon the retraction of the handle to follow;

FIGS. 10-16 illustrates a preferred embodiment of my invention wherein the machine element means for operating the crusher jaw is in form of a toggle link assembly, this form also having a vertically tapered configuration, FIG. 10 being a perspective view of this form;

FIG. 11 is a vertical side section with the jaws open, showing an uncrushed can in solid lines and a partially crushed can in broken lines in the position to which the can drops after the first stroke;

FIG. 12 shows the first stroke partially completed;

FIG. 13 shows the first stroke completed;

FIGS. 14 and 15 are sections taken as indicated on FIG. 13; and

FIG. 16 is a front view of the device.

Referring now to the embodiment of my invention shown in FIGS. 1-9 in more detail, the apparatus can be said to comprise five basic elements, namely a frame or fixed supporting means F, bearing a fixed jaw member A, a movable jaw member B fixed on a movable supporting means pivotally mounted on the frame, an operating lever or handle H, and machine element means indicated generally at E for causing motion of movable jaw B toward and away from fixed jaw A upon oscillation of the handle member H.

The frame and fixed jaw are both vertically mounted on a fixed support S (such as a wall, for example) and a container or tin can C to be crushed or flattened is also shown somewhat diagrammatically in each of FIGURES 1-9.

The frame F, includes a pair of side bars, 10, depending from the fixed jaw A, and there is a lateral pivot pin 11, that mounts the movable jaw B on the frame by means of a complementary pair of side bars or movable supporting means 12 depending from the movable jaw. Near the upper part of the movable jaw is an actuating pin 13 for connection of the movable jaw to handle member H. The handle member includes a pair of side bars 14 connected at their lower end by a tubular grip member 16. The upper end of each handle bar 14 is formed with sector teeth 17 that mate with teeth on curved sector plates 18 that extend forwardly (toward the operator) from the frame F, at the upper portion of the apparatus. Thus the mating toothed elements 17 and 18 and the pin 13 that connects the handle to the movable jaw form machine element means for moving the movable jaw toward

and away from the fixed jaw upon oscillation or "pumping" of the handle.

The angle of inclination of the fixed and movable jaws A and B is in the order of 22 degrees with the jaws open as in FIG. 2 and decreases slightly to about 17 degrees when the jaws are closed as in FIG. 3. The faces of the jaws therefore always converge downwardly when in engagement with a container, or if the movable jaw engages the fixed jaw in closed position in the absence of a container. The dimensions of the jaws and their maximum spacing depend upon the range of can sizes to be accommodated in the machine, for example the can shown in the drawings is about the smallest size that will fall through the jaws when they are open, as seen in FIG. 2.

In operation, an unflattened can C is dropped between the jaws and when the handle H is moved rearwardly to open the jaws the can drops to its lowermost position of FIG. 2. The first forward stroke of the handle nips the lower portion of the can and buckles the bottom (if the can is so inserted) into a V shaped member as seen in FIG. 3. This is easily accomplished because the jaws make localized, or substantially line contact with the can at the crushing positions, and as seen in FIG. 3, only a portion of the can is flattened on the first stroke of the handle.

The handle is then retracted as seen in FIG. 4 and the partially flattened can falls down through the jaws until a full diameter portion of the can catches in the lower jaw portions, ready for the next flattening stroke, the completion of which is shown in FIG. 5. The next retraction stroke with the can having again fed itself ready for another "nip" of the jaws is shown in FIG. 6, FIG. 7 shows the next crushing stroke, FIG. 8 the corresponding retraction stroke, and FIG. 9 the final crushing stroke. Upon the final retraction stroke (not illustrated) the flattened can drops clear of the apparatus.

For purposes of illustration, four crushing strokes are shown diagrammatically, but the number of strokes may be greater or less than four, depending upon the size of the can and the design of the working parts. The jaws are relatively smooth in the sense that they have no teeth or projections that will hold up the can and prevent it from feeding itself through the jaws under gravity, and because of the angle of relative inclination of the jaws referred to, the frictional force between the jaws and the can prevent the latter from popping up during the crushing stroke. The jaws, although relatively smooth in the functional sense referred to, may be roughened somewhat if desired by sand blasting, friction coatings or the like to augment the frictional grip on the can during crushing, so long as the jaws do not indent or penetrate the can enough locally to hold it upon the retract stroke.

FIGS. 10-16 show a preferred embodiment of the invention wherein the machine element means for causing the movable jaw to move toward and away from the fixed jaw in response to oscillation of the handle is in the form of a toggle link mechanism. In this form, the frame F' carries the fixed jaw A' but here the frame is formed by a pair of side plates 20, flanged at 21 to which flanges is welded a back plate 22, the upper portion of which forms the fixed jaw A'. The forward edges of each side plate 20 has a reverse bend 23 to pivotally receive side plates 24 of the movable jaw member B', by means of pivot pins 26. As best seen in FIGS. 14-16, the side plates 24 are flanged at 27 to mount a separate plate 28 welded to the flanges to form the crushing portion of the movable jaw B'. The angle of relative inclination of the fixed and movable jaws is like that described in the first form of the invention.

In order to operate the movable jaw by means of the handle H' a pair of toggle links 29 is provided, each link being pivoted between the handle and the frame (fixed jaw) by means of handle pivot pin 31 and frame pins 32, whereas the handle is pivoted to the movable

jaw by pivot pin 33. The three pivot points lie substantially in a straight line when the handle is retracted to the horizontal position shown in FIG. 11, and to permit this arrangement of parts each link 29 is notched as at 34 to clear the intermediate handle to movable jaw pivot pin 33.

When the handle is retracted this line of the pivot pins is almost perpendicular to the line between the fixed pivots 26 mounting the movable jaw on the frame and 10 the point 33 for the handle and the movable jaw. With this arrangement the mechanical advantage of the handle is virtually at its maximum, which is especially desirable at the initiation of a stroke where the bottom of the can must be crushed, as indicated in FIG. 12. (Of course 15 the same applies, but at a different time in the crushing cycle, if the can is lidless and has been inserted upside down.)

I prefer that the dimensions of the apparatus be such that the average container will not be one that initially 20 falls near the bottom of the jaws as in FIG. 2, but rather falls about midway or higher, as in FIG. 11, so that, as in FIGS. 11-13 the first stroke only partially folds the bottom of the can, this being the portion of the operation that requires the most force.

25 With the linkage arrangement shown, as the advance stroke of the handle continues the rate of advance of the movable jaw toward the fixed jaw likewise increases, but this is beneficial and efficient because, as mentioned, the most difficult part of the operation will be at the beginning of the stroke, and that part gets easier to perform as the stroke continues.

The length of link 29 is not critical but it should be noted that as such length is reduced from infinity, the amount of rotation imparted to the movable jaw by a 30 given rotation of the handle increases, and thus by making the link 29 relatively short, not only is the apparatus rendered compact, but the mechanical advantage at the beginning of the stroke is retained and adequate motion of the movable jaw is produced. It will be obvious that 35 while movement of the movable jaw may be limited by engagement with the fixed jaw, if the linkage is not constructed to allow movement of the movable jaw to that extent, the movement of the movable jaw will be limited by the linkage.

40 To give typical dimensions for a Number 2 can (3 $\frac{1}{4}$ inches in diameter) the pivot distance between pins 26 and 33 will be 11 inches, and links 29 will be 1 $\frac{1}{8}$ inches long with the distance between pins 31 and 33 being about half the length of the links. Obviously, as can be seen 45 from the drawings, the device as illustrated is operating on a certain diameter can, but both larger and smaller cans will be accommodated.

50 It will be noted in the form of FIGS. 10-16, that the fixed and movable jaws widen out from top to bottom. This accommodates the increase in can width as the latter 55 is flattened while providing optimum vertical guiding of the unflattened can.

Although the forms of the invention illustrated and 60 described are intended for manual operation of the handle, the handle could be power operated by any well known mechanism such as a crank and connecting rod connected to the handle that converts rotary to reciprocating motion.

Having completed a detailed description of two 65 embodiments of my invention so that those skilled in the art may practise the same, I claim:

1. A self feeding, progressive container crusher comprising a frame, a fixed crushing jaw on said frame, a movable crushing jaw, said jaws being generally vertically disposed and having relatively smooth container engaging faces, means for mounting said movable jaw on said frame for motion toward and away from said fixed crushing jaw, an operating arm, machine element means connected between said frame, said operating arm and said movable crushing jaw for moving said movable crushing

jaw toward and away from said fixed crushing jaw upon oscillation of said operating arm, said machine element means causing the crushing faces of said jaws to remain relatively inclined to form a gravity hopper at both the initial and final positions of said operating arm, at which positions said jaws are at their maximum and minimum relative spacings, respectively, successive advance and retract strokes of said arm moving said movable jaw back and forth between the same positions relative to said fixed jaw during the entire crushing operation, the advance strokes causing the lower, uncrushed portions of a container disposed between the jaws to be progressively flattened, with the container partially falling down and eventually out from between said jaws upon successive retract strokes, the minimum spacing of the lower portions of said inclined jaws being substantially equal to the thickness of the crushed container with the relative spacing of the remainder of the jaws exceeding said minimum spacing to accommodate the container until it is fully crushed, said machine element means comprising pivot means for pivotally mounting said arm to said movable jaw, and link means pivoted to said arm at one end and to said frame at the other end, said first named pivot means lying in between the pivots of said link means, and substantially in line therewith, when said operating arm and movable jaw are retracted, to give substantially maximum mechanical advantage to said arm when retracted.

2. A self feeding, progressive container flattener comprising a frame, a fixed flattening jaw on said frame, a movable flattening jaw, said jaws substantially flat and generally vertically disposed and having relatively smooth container engaging faces, means for mounting said movable jaw on said frame for motion toward and away from said fixed jaw, machine element means connected between said frame and said movable jaw for moving said movable jaw toward and away from said fixed jaw, said machine element means causing the faces of said jaws to remain relatively inclined to form a gravity hopper at the positions wherein said jaws are at their maximum and minimum relative spacings, respectively, successive advance and retract strokes of said movable jaw moving the movable jaw back and forth between the same positions relative to said fixed jaw during the entire flattening operation, the advance strokes causing the lower portions of a container disposed between the jaws to be progressively flattened, with the container partially falling down and eventually out from between said jaws upon successive retract strokes of the movable jaw, the minimum spacing of the lower portions of said inclined jaws being substantially equal to the thickness of a flattened container with the relative spacing of the remainder of the jaws exceeding said minimum spacing to accommodate the container until it is fully flattened, said fixed jaw having a pair of forwardly projecting container guiding side plates within which said movable jaw reciprocates, said fixed and movable jaws becoming progressively wider from their upper portions toward their lower portions to provide optimum lateral guiding for the unflattened and partially flattened container portions while accommodating the increase in container width as the latter passes through said jaws.

3. A self-feeding, progressive container flattener apparatus comprising fixed supporting means provided with a fixed container engaging jaw and a movable supporting means provided with a movable container engaging jaw, said movable supporting means being movable relative

to said fixed supporting means, means for moving said movable jaw toward said fixed jaw, force applying means to move said movable jaw toward said fixed jaw, said movable jaw to said closed position including stop means positively limiting movement of said movable jaw to said closed position, engaging jaws having substantially flat, generally vertically extending, relatively smooth container engaging faces, said supporting means supporting said jaws with said faces converging downwardly at a substantial angle in said closed position, said force applying means including an operating arm and machine element means connected between said operating arm and said supporting means to move said movable supporting means and movable jaw toward and from said fixed jaw so that the faces of said jaws form a gravity hopper with relatively movable converging sides in which a container descends on separation of said jaws, and in which a portion of a container is flattened between the lower portions of said jaws on movement of said movable jaw by said operating arm toward closed position.

4. A self-feeding, progressive container flattener apparatus comprising fixed supporting means provided with a fixed container engaging jaw and a movable supporting means provided with a movable container engaging jaw, said movable supporting means being movably mounted for pivoted movement relative to said fixed supporting means about an axis below said jaws to move said movable jaw toward said fixed jaw to closed position, and force applying means to move said movable supporting means and movable jaw to said closed position, said apparatus including stop means positively limiting movement of said movable jaw to said closed position, said container engaging jaws having substantially flat, generally vertically extending, relatively smooth container engaging faces, said supporting means supporting said jaws with the upper edges of said faces forming a larger angle at said axis as a center than the lower edges and with one of said jaws converging downwardly toward the other jaw at an angle to a radial plane through said axis and the upper edge of said one jaw so that said faces converge downwardly at a substantial angle in said closed position, said force applying means including an operating arm and machine element means connected between said operating arm and said supporting means to move said movable supporting means and movable jaw toward and from said fixed jaw so that the faces of said jaws form a gravity hopper with relatively movable converging sides in which a container descends on separation of said jaws, and in which a portion of a container is flattened between the lower portions of said jaws on movement of said movable jaw by said operating arm toward closed position.
